Primary Examiner — Vy N Koenig*Assistant Examiner* — Kimberly Barnes(74) *Attorney, Agent, or Firm* — Carrier Blackman & Associates, P.C.; Joseph P. Carrier; William D. Blackman(57) **CLAIM**

The ornamental design for a height-adjustable support assembly, as shown and described.

DESCRIPTION

FIG. 1 is an exploded perspective view of my new, original, and ornamental design for a height-adjustable support assembly;

FIG. 2 is a front elevational view as it would appear when assembled, the rear elevational view being identical to the front elevational view;

FIG. 3 is a right side elevational view thereof, the left side elevational view being identical to the right side elevational view;

FIG. 4 is a bottom plan view thereof; and,

FIG. 5 is a top plan view thereof.

The broken lines in the drawings illustrate portions of the height-adjustable support assembly that form no portion of the claimed design.
